Primary Examiner — Ian Simmons*Assistant Examiner* — Samantha Q Lawrence(74) *Attorney, Agent, or Firm* — Edward J. Baba; Bozicevic, Field & Francis LLP**CLAIM**

The ornamental design for bottle cap, as shown and described.

DESCRIPTION

FIG. 1 is a perspective view of the bottle cap showing our new design; and,

FIG. 2 is a top view of the bottle cap.

The broken lines are included for the purpose of illustrating unclaimed portions and form no part of the claimed design.
